UNITED STATES PATENT OFFICE.

ALLEN A. BOWSER, OF FORT WAYNE, INDIANA.

OIL-STORAGE APPARATUS.

1,160,106.

Specification of Letters Patent. Patented Nov. 9, 1915.

Application filed December 17, 1914. Serial No. 877,641.

To all whom it may concern:

Be it known that I, ALLEN A. BOWSER, a citizen of the United States, residing at Fort Wayne, in the county of Allen and State of Indiana, have invented certain new and useful Improvements in Oil-Storage Apparatus, of which the following is a specification.

This invention relates to the storage and discharge of oil, and the object of the present invention is to provide an improved construction for oil tanks in which a tank will be positively sealed at all times against the passage of vapors into the chamber or room containing the tank.

A further object is to provide improved means for venting several tanks or receptacles which may be assembled in an oil storage system in such a manner as to prevent the intermixture of vapors from different tanks and the formation of explosive mixtures, at the same time permitting the introduction of air into the said tanks to take the place of the oil drawn therefrom.

Other and further objects will appear hereinafter.

In the drawings, Figure 1 is a perspective of a storage system embodying a plurality of tanks constructed in accordance with the principles of this invention; Fig. 2 is a section through one of the tank units shown in Fig. 1; Fig. 3 is a perspective of one of the tanks or receptacles on a larger scale showing a barrel supporting track, the suction and return pipes, together with the pump, not being shown in this figure; Fig. 4 is a top plan view of the tank shown in Fig. 3, and Fig. 5 is a detail elevation of a portion of one of the vent means with a vent valve shown in section connected thereto.

A plurality of tanks 1, 2, 3, 4, 5 and 6 are shown in Fig. 1 arranged with their lateral walls abutting each other, each preferably rectangular in form and provided with a manhole cover 7 hermetically sealed about its edge to the top wall of the tank. Each of the manhole covers is provided with a fill opening in alignment with the fill openings of the other tanks, and suspended from each of the covers is a fill tube 8 which extends from the top to within a short distance of the bottom of the receptacle or tank and below the intake end of a suction pipe 13 so that the passage of vapors from the tube 8 is prevented by its lower end being sealed

with fluid, and the tube 8 and the pipe 13 are hermetically sealed with the top wall of the tank.

A barrel track 12 is supported above the tanks by means of standards 11, and this track extends over all of the tanks so that a barrel containing oil may be rolled thereon to discharge into any one of the file openings. The oil is discharged from the barrel through its bunghole, a fill pan 8' being provided for use in connection with the fill pipes to receive the direct discharge from the barrel, each of the fill pans being commonly provided with a removable screen. (Not shown in the drawings).

Any suitable pumping device, such as a pump 15 (see Fig. 1) may be provided for removing the oil from the tank, a separate pump commonly being connected to each suction pipe 13. In the embodiment shown in Fig. 1 the storage tanks are arranged below a discharging floor A, the pumps 15 (only one being shown) being each disposed to discharge into a drip pan 16 connected by means of a return pipe 17 with its respective tank. Each of the return pipes 17 is sealed about the top of its tank and extends within a short distance of the bottom of the tank and below the bottom of the suction pipe 13, thus maintaining a fluid seal for the pipe.

Each suction pipe 13 is provided with a strainer 14 but the extremity of the suction pipe, as before stated, is above the lower extremity of the fill pipe 8 and the return pipe 17 so that a fluid seal will be provided for the ends of these pipes at all times, even though the level of the fluid in the tank is just below the end of the suction pipe 13.

A vent pipe 19 is connected to a vent opening 18 in the top of each tank, and these vent pipes 19 are connected to a common header 20 which leads to an uptake 21 provided with a gooseneck 22 at the end disposed outside of the building in which the oil is stored, the gooseneck being commonly provided with a screen to prevent passage of flame thereinto. The gooseneck and screen are also for the purpose of protecting the header from the water, and from admission of dirt or foreign matter.

In each of the vent pipes 19 is a casting 23 having an aperture to form a seat for a valve 24. Each valve has a stem 25 slidable in an apertured partition 26 through which

vapors pass from the vent pipe. The valve is free to open upwardly to permit the discharge of air and vapor when the tank is being filled or by the expansion of vapor within the tank but prevents any vapor from the header from passing down into the tank, thus preventing explosive mixtures and all possible spontaneous combustion which might be caused by chemical action or mixture of the different vapors.

10 In order to provide means for permitting the entrance of air into each tank to displace fluid drawn therefrom the valve casting 23 is provided below the valve 24 with 15 a lateral extension 27 having a downwardly extending passage in which is a gland 28 for seating a ball 29 and constituting an inwardly opening ball valve. A screen 30 is held in place by the gland and provides a 20 safe-guard against fire. It will be noted that with this construction the ball valve is free to open upwardly to permit the entrance of air into each tank to displace fluid drawn therefrom but preventing vapor from 25 flowing outwardly through the ball valve and into the chamber or room in which the tanks are contained.

30 A tube 31 is secured to and extends through the top wall of each tank and extends within a short distance of the bottom of the tank so that it is always hermetically sealed by fluid in the tank, and a gage or measuring stick 32 is inserted in the pipe with a large cap 33 at the top which covers 35 the pipe and prevents the admission of dirt into the pipe.

40 In operation a barrel is rolled upon the barrel track and the contents discharged into any one of the fill openings and any one of the pumps 15 may be operated to discharge any one of the tanks. It will be apparent, however, that whenever operations may be in progress either filling or drawing the oil from the tank, or manipulating the 45 gage rod, the escape or intermixture of inflammable or explosive vapor into the storage chamber is absolutely prevented, since the end of the suction tube being disposed above the lower ends of the fill tube the 50 return tube and the gage rod maintains a fluid seal about the lower ends of the tube. If the expansion of the fluid or vapor in the tank causes a pressure therein the valve in the vent pipe 19 will be raised to permit the 55 discharge of the vapor. The gases are directed by means of the header 20 to a point without the building in which the tanks are located so that any vapor will not be confined in the tank chamber and there will 60 be no danger of explosion.

What I claim is:

1. Oil storage apparatus comprising a tank, a suction pipe having its intake adjacent the bottom of the tank, and a fill pipe extending below the intake of the suc-

tion pipe to form a fluid seal for preventing the escape of gases in the tank through the fill pipe.

2. Oil storage apparatus comprising a tank, a suction pipe having its intake adjacent the bottom of the tank, and a pipe for housing a depth gage sealed about and extending through the top of the tank to a point below the intake of the suction pipe to form a fluid seal for vapors within the tank.

3. Oil storage apparatus comprising a closed tank, a suction pipe having its intake adjacent the bottom of the tank, and a plurality of pipes, one of which is a fill pipe, sealed about the top of the tank and extending through the top to a point below the said intake to form a fluid seal whereby fluid may be discharged into the tank through the fill pipe at any time but preventing the discharge of gases from the tank through any one of said pipes.

4. In oil storage apparatus, the combination with a closed tank, of a suction pipe sealed in the tank having its intake adjacent the bottom and a fill pipe also sealed therein extending below the intake of the suction pipe to form a fluid seal for preventing the escape of vapors from the tank through said pipes, and an admission valve to admit air to displace fluid drawn from the suction pipe.

5. In oil storage apparatus, the combination with a closed tank, of a suction pipe sealed in the tank having its intake adjacent the bottom and a fill pipe also sealed therein extending below the intake of the suction pipe to form a fluid seal for preventing the escape of vapors from the tank through said pipes, a vent valve to permit the escape of vapor under pressure from the tank, and an admission valve to admit air to displace fluid drawn from the suction pipe.

6. In apparatus of the class described, a storage tank for oils, a fill pipe, a suction pipe, and a return pipe, all of said pipes opening into said tank at points adjacent the bottom of the tank, the other pipes opening below the suction pipe said tank being hermetically sealed about said pipes and closed except through said pipes.

7. In oil storage apparatus, the combination with a plurality of tanks, each provided with a fill pipe, of a suction pipe with a pump and a return pipe leading from said pump back to the tank, a vent pipe leading from each tank, and a common header with which all of said vents connect.

8. In oil storage apparatus, the combination with a plurality of tanks, each provided with a fill pipe, a suction pipe with a pump and a return pipe leading from said pump back to the tank, of a vent pipe leading from each tank, and a common

header with which all of said vents connect, said header being provided with a remote discharge opening.

9. In oil storage apparatus, the combination with a plurality of tanks, each provided with a fill pipe, a suction pipe with a pump and a return pipe leading from said pump back to the tank, of a vent pipe leading from each tank, and a common header with which all of said vents connect, said header being provided with an up-take discharging at a distance from the tanks and each of said vent pipes being provided with a valve between the tank and said header for preventing a back-flow from said header.

10. In oil storage apparatus, the combination with a plurality of tanks, each provided with a fill pipe, a suction pipe with a pump and a return pipe leading from said pump back to the tank, of a vent pipe leading from each tank, a common header being provided with an up-take discharging remote from the tanks and each of said tanks being provided with a valve between the tank and said header for preventing a back-flow from said header, and means for permitting the inflow of air from the space adjacent the tank for replacing the oil drawn from the tank.

11. In oil storage apparatus, the combination with an upper and a lower room, of a plurality of tanks in the lower room, a suction pump connected to each tank and disposed in the upper room, a vent pipe lead-

ing from each tank, a common header for 35 all of said vent pipes discharging outside of the rooms, a valve in each vent pipe and within the upper room, said valve being adapted to admit air from the room to the tank but to prevent a back-flow from the 40 header into the vent pipe.

12. In oil storage apparatus, the combination with a plurality of tanks each provided with a suction pipe through which the oil may be drawn at intervals, said suction pipe being provided with an intake opening adjacent the bottom of the tank, of a return pipe and a fill pipe connected with each tank, the last said pipes discharging below the intake opening of said suction pipe, thereby maintaining a fluid seal about the discharge openings of said fill and return pipes, valved vents for each tank to prevent excess pressure of vapor in the tank, a common header for the vents discharging 55 at a distance from the tanks, and an inlet valve for each vent to displace fluid drawn therefrom, whereby the vapor in the space above the fluid in each tank is maintained practically at atmospheric pressure.

In testimony whereof I have signed my name to this specification, in the presence of two subscribing witnesses, on this 14th day of December A. D. 1914.

ALLEN A. BOWSER.
